INVENTOR

Robert P. Jensen

BY

Pierre Barne

ATTORNEY

UNITED STATES PATENT OFFICE.

ROBERT P. JENSEN, OF SEATTLE, WASHINGTON.

FIREPLACE HEATER.

Application filed July 25, 1923. Serial No. 653,628.

To all whom it may concern:

Be it known that I, ROBERT P. JENSEN, a citizen of the United States, residing at Seattle, in the county of King and State of

5 Washington, have invented certain new and useful Improvements in Fireplace Heaters, of which the following is a specification.

This invention relates to fireplace furnaces for heating rooms and buildings, and 10 its object is the provision of a heater of this character which has all of the advantages of an open fireplace and a hot air furnace and which may be operated with a small consumption of fuel.

15 More specific objects and advantages of the invention will appear in the following description.

The invention consists in the novel construction, adaptation and combination of 20 parts hereinafter described and claimed.

In the accompanying drawings,—

Figure 1 is a view, partly in front elevation and partly in transverse vertical section, of my improved heating apparatus; 25 and Fig. 2 is a longitudinal vertical section of the same. Figs. 3, 4 and 5 are horizontal sections on broken lines 3—3, 4—4 and 5—5 of Fig. 2.

In said drawings, the reference numeral 30 10 represents a chimney supported upon the foundation of a building and extending upwardly through the floor 11 of a living room. Above said floor the chimney is provided with an open fireplace 12 having the 35 usual throat 13 which communicates with a chimney flue 14. 15 represents a damper for regulating the effective size of the throat 13.

In the basement below the floor 11, the 40 chimney structure is provided with a hot-air chamber 16 containing a stove or fire box 17 which is supported upon partitions 18 which with the fire box divide the lower portion of said chamber into an ash pit 19 45 below the fire box and a passage 20 at each side of the fire box and communicate with the chamber space above the latter.

Scoured inlets 21 provided in the side 50 walls 22 of the chimney admit air from the external atmosphere into the respective passages 20 at an elevation below the bottom of the fire box. The fire box is provided with an opening in its front through which fuel is supplied, said opening being provided with a door 23 which, as shown, is hinged at 24 and is adapted to be temporarily

held in its open position as by means of counterweights such as 25 suspended by a cable 26 passing over a guide pulley and connected to the door. 60

A grate 27 is provided in the floor of the fire box directly above the ash pit 19. 28 represents an ash chute extending downwardly from the fireplace and communicating at its lower end by means of a passage 29, Fig. 5, with the ash pit. A slideable door 30 is provided in passage 29 to prevent air entering into the ash chute and permits ashes to be removed through the ash pit and the opening 31 which is provided with a 70 door 32.

According to the present invention, the fire box 17 is provided with a stove pipe 33 having a branch outlet 33¹ into a flue 34 in the chimney and, above such outlet, the stove pipe has a connection 35 with a smoke and hot-air duct 36 having an outlet 37 through a wall of the fireplace into the latter. Above its outlet 33¹ the stove pipe is provided with an inlet branch 38 within the hot air chamber 16, the opening of said inlet branch having a damper 39 (Figs. 1 and 2) which is regulated by means of a cable 40 or an equivalent extending through the front wall of the chimney. 85

A damper 42 in the pipe outlet 33¹ and a second damper 43 in the stove pipe above the outlet 33¹ are respectively regulated by means of controlling rods 44 and 45 extending outside of the chimney structure. 90

46 represent hot air pipes extending from the hot air chamber 16 to rooms which are to be supplied with heat. These hot air pipes are provided with dampers (not shown) which may be in the nature of those employed in the usual floor or wall registers. 95

A vessel 47 (Fig. 1) to contain water is desirably provided within the hot air chamber 16 to furnish humidity to the air therein. 100 48 represents a pipe-coil provided in the fire box 17 to supply hot water for domestic purposes.

In the use of my invention, the stove 17 and the fireplace 12 may be operated either 105 separately or together by a suitable regulation of the several dampers. When the stove is employed, air admitted through openings 21 and passages 20 at opposite sides of the stove into the heating chamber 16 becomes 110 hot by radial heat from the fire in the stove.

When a fire is started in the stove, the

damper 43 (Fig. 1) is closed and damper 42 opened to cause the smoke from the stove to be delivered into the chimney flue 34. With the dampers 42 and 43 thus arranged and by 5 opening the damper 39 the hot air from chamber 16 is permitted to escape through the passage 36 into the fireplace and is directed through the latter into the room containing the fireplace. When the hot air is 10 thus delivered through the fireplace, the throat damper 15 thereof is advantageously closed to afford the maximum efficiency.

After the fire in the stove is burning properly the damper 42 is closed and dampers 15 43 and 15 opened whereby the hot combustion products—smoke and gases—from the stove are conducted through the duct 36 and fireplace 12 to the chimney flue 14 so that the heat from such combustion products 20 may be utilized in the fireplace for warming the adjacent room.

Under the conditions above explained the hot air from the heating chamber may be caused to accompany the smoke by allowing 25 the damper 39 to remain open, or the damper 39 may be closed and the hot air from the chamber 16 can be discharged through outlets 46 for delivery through registers above mentioned.

30 While any suitable fuel can be used in the stove, best results are believed to be obtainable with wood fuel.

The operation and advantages of the invention will, it is thought, be understood 35 from the foregoing description.

What I claim is,—

1. In a chimney having a fireplace, a flue therefor, an air heating chamber, a second flue, and an inlet passage for said fireplace, 40 a stove provided in said chamber, a stove pipe connecting said stove with said second flue and also with said passage, a system of dampers provided for said pipe, and means for regulating said dampers whereby smoke 45 products from the stove may be directed, selectively, into the second named flue or into said passage.

2. In a chimney having a fireplace, a flue therefor, an air heating chamber, a second flue, and an inlet passage for said fireplace, 50 a stove provided in said chamber, a stove pipe connecting said stove with said second flue and also with said passage, said pipe having an air inlet communicating with the 55 space in the chamber surrounding said pipe,

a system of dampers provided for said pipe, and means for regulating said dampers whereby smoke products from the stove may be directed, selectively, into the second named flue or into said passage, said means 60 also controlling the dampers to effect the delivery of hot air into said passage from said chamber accompanied by the smoke products from the stove.

3. In a chimney having a fireplace, an air 65 heating chamber below the fireplace, a passage communicatively connecting said chamber with the fireplace, a stove provided in said chamber for heating the air in the latter, and means for regulating the admission 70 of air into said passage from the chamber, and damper devices for controlling the combustion of fuel in the stove.

4. In a chimney having a fireplace, an air 75 heating chamber below the fireplace, and a communicative connection between said chamber and the fireplace, a stove provided in said chamber, a stove pipe for said stove communicating with a flue of said chimney and also with said passage, said pipe having 80 an air inlet from said chamber, and a system of dampers provided for said pipe whereby smoke from the stove may be delivered selectively into said flue or into said passage, or air from said chamber delivered 85 into the passage exclusive of smoke.

5. In a chimney having an open fireplace, an air heating chamber below said fireplace, and smoke flues provided for the fireplace and said chamber, said chimney being provided 90 with a passage leading from said chamber into the fireplace, said chimney being provided with openings to admit air into the lower portion of said chamber, a stove provided in said chamber, a stove pipe for 95 the stove, said stove pipe having branch outlets connected with the smoke flue of said chamber and with said passage respectively, dampers provided in the respective outlets of the stove pipe, a hot air inlet provided 100 for the stove pipe intermediate the branches thereof, and a damper for said air inlet to regulate the effective size of the latter.

Signed at Seattle, Washington, this 27th day of June, 1923.

ROBERT P. JENSEN.
